UNITED STATES PATENT OFFICE

142,112

DESIGN FOR A GAME BOARD

Stephen G. O'Leary, Detroit, Mich.

Application January 25, 1945, Serial No. 117,589

Term of patent 14 years

(Cl. D34—5)

To all whom it may concern:

Be it known that I, Stephen G. O'Leary, a citizen of the United States, residing at Detroit, in the county of Wayne and State of Michigan, have invented a new, original, and ornamental Design for a Game Board, of which the following is a specification, reference being had to the accompanying drawing, forming part thereof.

In the drawing:

I claim:

The ornamental design for a game board, as shown.

STEPHEN G. O'LEARY.
